UNITED STATES PATENT OFFICE.

JOHN LUCAS AND GUSTAV SCHLIEFFKA, OF PITTSBURGH, PENNSYLVANIA.

JARRING-MACHINE.

1,234,050.

Specification of Letters Patent. Patented July 17, 1917

Application filed April 8, 1917. Serial No. 160,665.

To all whom it may concern:

Be it known that we, JOHN LUCAS and GUSTAV SCHLIEFFKA, residents of Pittsburgh, in the county of Allegheny and State of Pennsylvania, have invented a new and useful Improvement in Jarring-Machines, of which the following is a specification.

The invention relates to jarring machines.

It is highly desirable in foundry practice 10 to have some kind of a machine by means of which the molds may be jarred to settle the sand about the patterns. Various types of machines have been proposed, all of which are rather complicated, occupy considerable space and each of which must have a separate mechanism for furnishing the power to jar the molds which in many cases is quite heavy. The present invention has been devised to avoid the difficulties and 20 expense of having a large number of complicated and bulky jarring machines.

The general object of the invention is to provide an improved jarring machine which may be operated by simply attaching to it 25 the hook of a traveling crane, such as is usually present in a foundry.

Another object is to provide an improved jarring machine which is simple, compact, inexpensive and easily operated.

30 A further object is to provide a jarring machine with an improved attachment by means of which the sand may be jarred out of the molds.

Other objects and advantages of the invention will appear from the following 35 specification.

An embodiment of the invention is shown in the following drawings, the views of which are as follows:—

40 Figure 1 is a diagrammatic view showing the jarring machine as it is operated by the traveling crane for jarring the sand about the pattern, and, also, for jarring the sand out of the mold.

45 Fig. 2 is a cross section through the jarring machine.

Fig. 3 is a cross section at right angles of Fig. 2.

50 Fig. 4 is a section on the line 4—4 of Fig. 2.

Fig. 5 is a detail section through the ratchet mechanism.

Fig. 6 is a side elevation, showing the attachment for jarring the machine, in section.

Fig. 7 is an end elevation showing the attachment in section at right angles to the section in Fig. 6.

The machine comprises in general a frame 1, rigidly attached in any suitable manner 60 to a floor, a reciprocable jarring table 2 and mechanism arranged to be operated by the traveling crane 3 for jarring the table.

The frame 1 may be of any suitable shape and made of any suitable material. Preferably, it is made of metal and is rectangular in shape, being constructed in two parts 4 and 5 which are bolted, or otherwise fastened together, when the machine is assembled. The lower half 4 is fastened to the 70 floor of a foundry by bolts 6, or by any other suitable means. The upper half carries a bearing sleeve 7 supported by ribs 8 which extend from the side walls of the frame to the sleeve. This sleeve is perfectly cylindrical in shape and arranged to receive the post or pedestal 9 of the reciprocable table 2. The sleeve and pedestal have complementary recesses 10, in which a key 11 is positioned. This permits the pedestal 80 to slide in the sleeve but prevents it from rotating.

The jarring table 2 fits on top of the upper half 5 of the frame with its pedestal 9 positioned in the sleeve 8, the lower end of 85 the pedestal having a link or connecting rod 12 connected to it which in turn is pivoted to a cam lever 13.

The lever 13 is carried in this instance by the shaft 14 journaled between a downwardly projecting rib on the upper half 90 of the frame and ribs 16 extend between the end walls of the lower half of the frame. The free end of the lever is provided with a cam surface 17 which is arranged to be 95 engaged by the cam surfaces of a two-armed cam 18 carried by shaft 19 that is journaled in the lower half 4 of the frame. Whenever the shaft 19 is rotated the cam 18 engages the surface 17 of the lever 13 and 100 moves it upwardly to raise the table. As the cam 18 passes beyond the surface 17 it permits the lever and the table with the mold on top of it to suddenly drop against

the frame of the machine, thereby suddenly jarring the mold and settling the sand about the pattern.

The ends of the shaft 19 project beyond the sides of the frame and on each end there is mounted a ratchet drum 20. These drums are loosely journaled on the shaft and each carries a dog or tooth 21 biased by a spring 22 into engagement with the ratchet wheel 23 which is fixed rigidly to the shaft. Accordingly when the drums are rotated in one direction the shaft 19 is turned but when they are rotated in the other direction the tooth 21 simply rides over the teeth on the ratchet wheel 23 without rotating shaft 19.

Wound about each of the drums are cables 24 and 25, said cables being preferably attached to the drum at one point. One end 20 of each of the cables carries a ring or hook 26 by means of which it may be attached to the hook of the traveling crane and the other end of each of the cables is attached to a weight 27 which serves to normally rotate the drum after the cable has been disconnected from the crane so as to wind about the drum the end of the cable which is arranged to be attached to the crane in order that the mechanism will be automatically maintained in a condition to be operated by simply attaching the crane hook to the ends of the cable. The weights 27 are shown as operating in openings 28 in the foundry floor, though of course these 30 weights may be otherwise located and the cables run over suitable pulleys as may be found desirable. It is also to be understood that any other suitable means may be used for returning the drums to their normal 40 position with the cables wound thereabout.

The ratchet drums 20 are housed in casings 30 which are attached to the frame of the machine and which serve to protect the drums and prevent dirt gaining access to them. The cables 24 and 25 pass through suitable openings in these housings.

The machine herein illustrated is provided with a drum on each end of the shaft 19 and two cables which are connected to 50 the crane by means of a spreader 32. This balances the pull on the machine and is the preferable construction, though it may be varied in any convenient way.

It will be observed that with the construction above described, the lifting force of the crane or other device which is attached to the cable is applied to the jarring table with increased intensity, owing to the leverage that is secured. The extent of this 60 leverage may be varied if necessary. It is particularly advantageous for the reason that some of the molds to be jarred are exceedingly heavy and consequently any mechanism which converts the pulling force 65 of the crane into a force of increased intensity acting over a short distance is highly desirable.

The manner in which these jarring tables are used is as follows.—

Tables are positioned at convenient points 70 around the foundry and, as will be observed, are of a convenient height so that a mold may be easily placed on top of the jarring table 2. In practice a pattern is laid on the jarring table, or on a board laid 75 thereon, a flask is then put around the pattern and sand is shovelled into the flask. The crane hook is then attached to the ends of the cables and the hook raised to pull the cables upwardly. This rotates the 80 ratchet drums and causes the ends of the cam 18 to successively engage the pivoted lever to jar the table 2. The cables are preferably made of such length that a single movement of them upwardly rotates 85 the shaft a sufficient number of times to properly jar the mold, though, of course, if the mold is not sufficiently jarred the crane hook may be lowered and raised again.

When the operation is completed the 90 cables are unhooked from the cranes and the weights 27 automatically wind them about the drums so that the machine is immediately and automatically placed in condition for another operation. In the 95 meantime, the crane operator moves the crane to the succeeding table and jars that table in the same manner.

It will readily be understood that this avoids the necessity of having a separate 100 pneumatic, electric or other operating means at each of the jarring tables which is not only expensive but requires considerable space at each machine. The simple structure herein described is inexpensive 105 and consequently quite a number of these machines may be placed about a foundry in all convenient positions for the molding. They may then be quickly and easily operated by simply running the traveling crane 110 over to their location, hooking onto the cable and giving the cable a pull upwardly.

In order to jar the sand out of a mold the attachment shown in Figs. 6 and 7 has been 115 provided.

This attachment is arranged to set on top of the jarring table 2 and for this purpose it has a flanged base 35 carrying two uprights 36 and 37, each of which has a series of notches 38 therein forming steps 120 or shoulders for receiving a mold 39. A trough or chute 40 is positioned about the uprights to direct the sand from the center of the attachment to the sides of the jarring machine. For this purpose it is sloped 125 in both directions from the center. The attachment is used by simply placing it on the jarring table, putting the mold in the attachment, hooking the crane onto the cable of the machine and pulling upwardly. 130

The operation jars the table and thereby jars the sand out of the mold into the chutes which direct it to the sides of the machine. The attachment may be easily 5 removed and the machine used for jarring a mold as first described.

The advantages of this machine are that it is simple, inexpensive, durable, occupies 10 very little space, may be used for jarring sand about a pattern as well as jarring the sand out of a mold and in addition it may be operated by the usual crane that is found in practically all foundries. It is unnecessary to provide an electric, steam or pneumatic 15 motor for operating each of the jarring machines and the expense incident to such power installations is avoided.

It is to be understood that the structure 20 shown is for the purpose of illustration and that other structures may be devised which come within the spirit and scope of the appended claims.

What is claimed is:—

1. A jarring machine comprising a compact frame arranged to be attached to a floor or the like, a movable table carried thereby, and means on the frame adapted to be actuated by a crane for jarring the table. 25
2. A jarring machine comprising a compact frame arranged to be attached to a floor or the like, a reciprocable table carried thereby, and means carried by the frame and located beneath the table and arranged to be actuated by a crane to jar said table. 30
3. A jarring machine comprising a frame, a movable table carried thereby, a cam mechanism for jarring said table and mechanism adapted to be operated by a traveling crane for actuating the cam mechanism. 35
4. A jarring machine comprising a frame, a reciprocable table carried thereby, a pivoted lever attached to the table by a connecting rod and having a cam surface, a shaft carrying a cam arranged to oscillate the lever, and means attached to the shaft arranged to be operated by a crane to rotate the shaft and cam to oscillate the lever and jar the table. 40
5. A jarring machine comprising a frame, a reciprocable table carried thereby, cam mechanism arranged to jar the table including a rotatable shaft and a ratchet drum associated with the shaft and carrying a cable having one of its ends arranged to be attached to a crane whereby the shaft may be rotated to operate the cam mechanism to jar the table. 45
6. A jarring machine comprising a frame, a reciprocable table carried thereby, cam mechanism for jarring the table including a shaft, and ratchet drums carried by the shaft having cables attached thereto adapted to be connected to a crane whereby the drums may be rotated to rotate the shaft to

operate the cam mechanism to jar the table, 65 said drums being normally biased to position the cable so that the end of the cable to which the crane is attached is wound about the drum.

7. A jarring machine comprising a frame, 70 a table having a pedestal arranged to reciprocate in a bearing in the frame, a pivoted lever carried by the frame and attached to the pedestal by a connecting rod, said lever having a cam surface, a shaft journaled in the frame, a cam carried by the shaft and adapted to oscillate said lever to jar the table, ratchet drums mounted on the ends of the shaft, each of said drums having a cable wound thereabout one end of which is adapted to be attached to a crane and the other end being provided with means for normally rotating the drum so as to wind about the drums the end of the cable that is arranged to be attached to the crane. 85

8. The combination with a traveling crane of a jarring machine comprising a compact frame arranged to be attached to a floor or the like, a movable table carried by said frame, and means on the frame and beneath the table arranged to be actuated by a crane for jarring the table. 90

9. The combination with a traveling crane of a jarring machine comprising a frame, 95 a vertically, reciprocable table, a cam mechanism for jarring the table and means arranged to be operated by the crane for actuating the cam mechanism to jar the table.

10. The combination with a jarring machine having a jarring table adapted to receive a pattern and mold so that the sand may be jarred about the pattern, of a frame 100 arranged to be removably fitted on said table to support a mold so that the sand may be jarred therefrom. 105

11. The combination with a jarring machine having a frame provided with a jarring table, of an attachment adapted to be positioned on said table and arranged to receive molds of various sizes to support them 110 so that the sand may be jarred therefrom.

12. A jarring machine comprising a frame, a movable table carried thereby, and means adapted to be actuated by a traveling crane for jarring said table, said means being arranged to apply the lifting force of the crane with increased intensity to the lifting table. 115

13. A jarring machine comprising a frame, a movable table carried thereby, and means adapted to be actuated by a traveling crane for jarring said table, said means being arranged to apply the lifting force of the crane with a leverage on the lifting table. 120

14. A jarring machine comprising a frame, a movable table carried thereby, and cam mechanism adapted to be actuated by a traveling crane for jarring said table, said

cam mechanism being arranged to apply the lifting force of the crane with a leverage on the lifting table.

15. The combination with a traveling crane, of a jarring machine comprising a frame, a movable table carried thereby, and means adapted to be actuated by the crane for jarring said table, said means being arranged to apply the lifting force of the

crane with increased intensity to the lifting table.

In testimony whereof, I have hereunto set my hand.

JOHN LUCAS.
GUSTAV SCHLIFIKA.
